UNITED STATES PATENT OFFICE.

GUS F. ROBERTS, OF FRIES, VIRGINIA.

ROVING-CLAMP FOR SPINNING-MACHINES.

1,110,716.

Specification of Letters Patent. Patented Sept. 15, 1914.

Application filed March 11, 1914. Serial No. 823,963.

To all whom it may concern:

Be it known that I, GUS F. ROBERTS, a citizen of the United States, residing in Fries, in the county of Grayson and State of Virginia, have invented certain new and useful Improvements in Roving-Clamps for Spinning-Machines, of which the following is a specification.

My invention relates to the devices employed in spinning machines for effecting a second breakage of the roving on the receiving side of the drawing rolls whenever the thread has been broken or becomes slack on the delivery side thereof.

As is well understood, such devices are employed for the purpose of preventing the waste of roving or damage to the rolls when the threads break between the rolls and the spindles which normally receive them.

In such mechanism the roving usually passes from bobbins carried by a creel through guides carried by a reciprocating traverse bar to the drawing rolls and then to guides formed on the ends of wires which are so connected with devices for breaking the thread at the rear side of the drawing rolls that normally while the machine is in operation said clamps or breaking devices are inoperative, but the arrangement is such that, when a thread breaks on the delivery side of the rolls said wire, or as it is generally called "drop wire" which is normally held elevated by the thread will drop and cause the clamp or thread-breaking devices to operate to break the roving at the receiving side of the drawing rolls and thus stop the feed of roving through the rolls and prevent the piling up of threads or the entanglement thereof with the mechanism.

In such machines the threads after passing from the drop wires usually pass through guides arranged over spindles on which the thread is wound.

In my U. S. Patent No. 1,088,036, of Feb. 24, 1914 I have shown novel mechanism of this kind which is very sensitive in operation and is of such nature that the drop wire has a thread-engaging end which is so balanced as to merely make lateral contact with the thread without exerting a vertical strain thereon, and which drop wire is mounted in bearings in such manner that it moves about an axis transverse to the axes of the drawing rolls. Such a device has been found to be most efficient in operation.

The part of the drop wire through which

the thread from the rolls passes is made adjustable in order that it may be properly related to the thread and the thread-engaging end of the drop wire is so constructed that the thread may be easily engaged therewith when taut but cannot be easily disengaged therefrom when the thread is loose. I also provide means supported on the traverse bar by which the roving clamps may be held up or out of engagement with the roving when the machine is being doffed.

My improvements are shown in the accompanying drawings, in which:

Figure 1 shows a vertical section of a portion of a spinning machine with my improvements applied, the guides being in the position which they occupy when the roving is being drawn through the drawing rolls and the thread is being properly passed to the spindles. Fig. 2 is a perspective view illustrating the construction of the clamp proper and the devices for supporting and operating it. Fig. 3 is a detail view in perspective, showing devices for securely fastening the frame of the roving clamp to the traverse bar. Fig. 4 is a detail view in perspective of the end of the drop wire which is engaged by the thread issuing from the drawing rolls. Fig. 5 shows a section on the line 5—5 of Fig. 4. Fig. 6 shows a section on the line 6—6 of Fig. 4. Fig. 7 is a perspective view of the front portion of the bearing for the drop wire. Fig. 8 shows an elevation thereof. Fig. 9 is a detail view in perspective of the devices for holding the roving clamps in their elevated position during doffing. Fig. 10 is a detail view in section thereof.

The drawings show my improvements applied to drawing rolls of usual construction. These rolls A are supported on a roll beam B by standards C in the usual way. The traverse bar D which is operated in the usual manner is arranged in rear of the drawing rolls, and on this bar in rear of each of the rolls is secured a frame E, provided at its upper end with a guide e while at its lower end it is bent or doubled at e' and carried upwardly and then rearwardly, as indicated at e², where it is again bent upwardly at e³. In order to securely fasten the frame E to the traverse bar I bolt it thereto at d, but as the bolt may loosen I provide an additional attaching device consisting of a bent wire I, having a top portion i (Fig. 3) which extends above the

traverse bar and over the upper portion d' of the frame E. This upper portion of the wire clip is formed with vertical portions i' , which extend down in front of the traverse bar and connect with rearwardly extending portions i^2 which project under the traverse bar and are bent slightly upward on the front side of said bar. This wire clip is so applied to the traverse bar and to the frame E that the frame is securely fastened to the traverse bar and even should the bolt loosen there is no danger of the frame being displaced.

The roving clamp G is pivoted at g to a bracket F which at its lower rear end is doubled at f and formed with an upwardly projecting portion f' provided with an eye f^2 for the roving X. The bracket is adjustably secured to the upwardly projecting portion e^3 of the frame E by a bolt H extending through a slot h in said upwardly projecting portion e^3 and engaging said bracket. In this way the bracket may be adjusted vertically to give the desired vertical adjustment to the clamp and to thus vary its position with reference to the rod O which operates it. In this way also the eye f^2 is at all times retained in a plane coincident with that of the top of the bracket. It will be observed that when the bracket with the clamp is vertically adjusted the eye f^2 is correspondingly adjusted so that the relation between the clamp, the bracket and the eye is always maintained the same.

The clamp G is operated by the rod O above referred to and which is shown in perspective in Fig. 2. This rod is connected to the crank n formed on the rear end of the drop wire L. As shown in Fig. 2 the rod O has a substantially horizontal portion o connecting with a substantially vertical portion o' which is bent at o^2 and projected upwardly at o^3 where it passes through a hole o^4 in the bracket F in such manner that when the rod is moved vertically it will cause the clamp G to rise and fall. By forming the rod in the manner shown the frame E is cleared; that is, the rod does not come in contact with the frame to produce any undue friction or binding and yet the rod is properly guided in the bracket and engages the roving clamp in such manner as to normally hold it in an elevated position. When the drop wire is released by the thread it turns easily in its bearings and the rod O descends without undue friction and allows the roving clamp to drop of its own weight and engage the roving. By bending the rod O in the manner specified away from the crank arm the weight of the rod is applied vertically to the crank arm and assists in the operation of applying the clamp to the roving.

The drop wire L is mounted to move about an axis transverse to the axes of the

drawing rolls. Its rear bearing consists of a plate R attached to the frame E. The front bearing of the drop wire consists of a bar M firmly attached by the nuts m to the frame E extending forwardly therefrom and bent at m^2 and extending downwardly as shown. In this way space is left beneath the front drawing rolls to accommodate a cleaning roll when such is required.

I have found that it is desirable to provide some means for adjusting the front bearing of the drop wire vertically in order that its thread-engaging end may be properly related to the thread.

Inasmuch as the mechanism is supported entirely on the traverse bar the relation between the engaging end of the drop wire and the thread may vary and an adjustment of this relation is desirable. For the purpose of this adjustment I preferably provide a plate M', having an aperture m^4 through which the drop wire L passes and having a slot p to accommodate a set screw P which engages the downwardly projecting portion m' of the rod M. This rod is slotted at m^6 to accommodate the drop wire, and the arrangement is such that by adjusting the plate M' up or down the thread-engaging end L' of the drop wire may be raised or lowered as occasion may require. The thread T passes from the drop wire through a guide U to a spindle V in the usual way. This guide U is raised during doffing and it may be hinged at u for this purpose. The drop wire is so related to the drawing rolls and to the guide U that the thread T normally passes through the thread-engaging end of the drop wire in such manner as to exert no vertical strain or weight thereon but during doffing or when the guides U are raised the threads will be raised also out of their normal position and will become loose and might become disengaged from the drop wires and delay the operation. In order to prevent this, I form the thread-engaging ends of the drop wires in the manner indicated in Fig. 1 and also in Figs. 4 to 6, inclusive. As shown, the drop wire is bent upwardly at its front end, forming a front portion l , l' which is bent at its upper end y with an intervening space between the parts l' , l^2 . The wire is bent again at l^4 , forming a lower loop at this point and then is continued upwardly at l^5 , being made to enter the space between the parts l' , l^2 , as indicated in Figs. 4 and 5. Normally the thread T passes freely through the lower portion of the thread-engaging end L' of the drop wire, as indicated in Figs. 1 and 6 and barely touches said thread-engaging end but if the thread becomes loose or is raised, as when the guide U is elevated, it will pass into engagement with the members l' , l^2 , l^3 , as indicated in Fig. 5. This engagement is such as to prevent the thread

from easily passing out of the drop wire. The thread being in a loose condition at this time it will be detained in engagement with the drop wire. Furthermore, the construction is such, as clearly shown in Fig. 4, 5 that a thread while being rotated or twisted, and being drawn rapidly forward may easily be brought into engagement with the thread-engaging end L' . I have found this 10 construction of drop wire most efficient in operation and this particular construction may be used in drop wires of various kinds.

When the machine is being doffed and when the thread is loose, it is desirable to 15 hold the drop wires in an elevated position, said wires at this time not being so held by the thread itself. For this purpose I provide the holding or locking devices shown in Figs. 1, 9 and 10 of the drawings. Below 20 the plane of the traverse bar D and in rear thereof I mount a horizontally arranged shaft S which may extend from one end of the spinning frame to the other past several sets of drawing rolls. This shaft may 25 be supported in brackets S', a suitable number being provided for the purpose arranged at suitable intervals apart. Each of said brackets is firmly attached to a suitable number of frames E in the manner shown.

30 Each bracket, as shown in Fig. 9, is provided with a part s through which the rear end of the rod M extends and this part of the bracket S' is held on said rod M and in engagement with the frame E by one of the nuts 35 m. From the upper portion s the bracket S' extends downwardly and rearwardly to receive the shaft S which shaft is provided with an operating rod S². This rod may normally occupy the position shown by dotted lines in Fig. 1 but when the machine is 40 being doffed it may be moved to the position shown by full lines and made to engage a suitable catch or latch S³ carried by the creel member or creel frame J. The shaft 45 S carries drop wire-engaging arms K, shown most clearly in Figs. 9 and 10. One such arm is provided for each drop wire and said arm is preferably constructed of thin sheet metal in order to make it light and 50 thus not unduly increase the total weight carried by the traverse bar. Preferably each such arm comprises a portion k which is bent around the shaft S and then doubled at k' to thicken it and provide a firm hold 55 for the screw k² which serves to clamp the arm on the shaft. The outer end of the arm is bent upwardly at k³ and notched at k⁴ for the purpose of readily engaging the crank arm n of the drop wire. In the normal operation of the machine the drop wire holding devices do not engage the drop wires 60 but when the machine is being doffed the operating rod S² is turned to the position shown in Fig. 1, made to engage the latch S³ and in this position it will hold the drop

wires in an elevated position and will also hold the clamp G out of contact with the roving. In recommending the operation the operating rod S² is moved to the position shown by dotted lines in Fig. 1 and the 70 drop wires are then all held up by the thread which is then under tension and rapidly being fed forward to the spindles D.

It will be noted that in my improved mechanism the clamps operate on the roving 75 at a considerable distance from the drawing rolls and not close thereto as in some prior machines.

It will also be noted that when the bracket F is adjusted vertically on the frame E the eye f², is correspondingly adjusted so that the guiding eye always maintains the same relative position to that part of the bracket over which the roving passes and on which it is clamped. 85

I claim as my invention:—

1. The combination with the drawing rolls of a spinning machine, of a clamp for the roving in rear of the rolls, a drop wire having a thread-engaging end formed by bending the wire to provide a loop through which the thread freely passes and a free yielding portion for closing the loop at its upper end. 90

2. The combination with the drawing rolls 95 of a spinning machine of a clamp for the roving in rear of the rolls, a drop wire having a thread-engaging end formed by bending the wire to provide three vertical portions, the middle one of which extends to a 100 position between the other two.

3. The combination with the drawing rolls of a spinning machine of a clamp for the roving in rear of the rolls, a drop wire having a thread-engaging end in front of the 105 rolls which is so balanced as to merely make lateral contact with the thread without exerting a vertical strain thereon, bearings in which the drop wire is mounted to move about an axis transverse to the axes of the 110 drawing rolls, connections between the drop wire and the clamp whereby the latter is normally held out of engaging position with the roving but which allows the clamp to engage the roving when the thread issuing 115 from the rolls breaks, and means for adjusting said bearings vertically to raise and lower the thread-engaging end of the drop wire. 120

4. The combination with the drawing rolls 125 of a spinning machine of a clamp for the roving in rear of the rolls, a drop wire having a thread-engaging end in front of the rolls, a rear bearing for the drop wire and a front bearing for said wire, comprising a stationary member and a vertically adjustable member through which the wire extends.

5. The combination with the drawing rolls 130 of a spinning machine of a clamp for the

roving in rear of the rolls, a drop wire having a thread-engaging end in front of the rolls, a rear bearing for the drop wire, and a front bearing for said drop wire, comprising a bar having a downwardly extending front portion and a vertically adjustable plate carried by said front portion.

6. The combination with the drawing rolls of a spinning machine of a clamp for the roving in rear of the rolls, a drop wire having a thread-engaging end in front of the rolls, bearings in which the drop wire is mounted to move about an axis transverse to the axes of the drawing rolls, a crank on the rear end of the drop wire and a rod pivotally connected with the crank having a laterally projecting portion, a vertical portion extending upwardly from said laterally projecting portion, an inwardly projecting part at the upper end of said vertical portion and another vertically extending part adapted to engage the clamp.

7. The combination with the drawing rolls of a spinning machine of a reciprocating traverse bar, a frame bolted thereto, a wire clip for fastening the frame to the traverse bar, a clamp for the roving supported on said frame, and a drop wire also supported on said frame.

8. The combination with the drawing rolls of a spinning machine of a traverse bar, a frame securely fastened thereto, a bracket formed with a guide-eye for the roving carried by said frame and vertically adjustable thereon, a clamp pivoted to said bracket, a drop wire also supported on said frame and having a crank arm at its rear end, and a bent rod connecting said crank with said clamp.

9. The combination with the drawing rolls of a spinning machine of a reciprocating traverse bar, clamps for the roving in rear of the drawing rolls, drop wires having thread-engaging ends in front of the rolls, connections between the drop wires and the clamps, clamp-supporting frames attached to the traverse bar, drop wire-supporting

bars M supported by said frames and having threaded ends extending through the frames, nuts on opposite sides of said frames for securing the supporting bars to said frames, brackets (S') attached to said clamp-supporting frames by the same nuts that attach the drop-wire-supporting bars to the frames, and means for holding the clamp out of contact with the drawing rolls during dossal comprising a shaft mounted to turn in said brackets (S'), a series of notched arms carried by said shaft and adapted to engage the drop wires, an operating lever carried by said shaft, and a latch for holding the clamp in position when the shaft is operated to support the drop wires.

10. The combination with the drawing rolls of a spinning machine of a clamp for the roving, a reciprocating traverse bar, a clamp-supporting frame secured to the traverse bar, a bracket to which the clamp is pivoted which is formed with a guiding eye for the roving and which is adjustable vertically on the clamp-supporting frame, the arrangement being such that when the bracket is adjusted vertically the guiding eye is coincidentally adjusted.

11. In a spinning machine the combination of the drawing rolls, a spindle to which the thread passes from the drawing rolls, a guide for the thread arranged immediately over said spindle, a clamp for the roving in rear of the drawing rolls, a drop wire having a thread-engaging end in front of the rolls and between them and said guide, connections between the drop wire and the clamp, and a bearing for the drop wire supported by the traverse bar of the machine which is vertically adjustable to vary the position of the thread-engaging end of the drop wire.

In testimony whereof, I have hereunto subscribed my name.

GUS F. ROBERTS.
